UNITED STATES PATENT OFFICE.

HARRY W. HILL, OF CLEVELAND, OHIO.

DESIGN FOR A PILLOW-BLOCK STANDARD.

SPECIFICATION forming part of Design No. 21,613, dated June 7, 1892.

Application filed March 10, 1892. Serial No. 424,451. Term of patent 14 years.

To all whom it may concern:

Be it known that I, HARRY W. HILL, a citizen of the United States, residing at Cleveland, in the county of Cuyahoga and State of Ohio, have invented and produced a new and original Design for Pillow-Block Standards, of which the following is a specification, reference being had to the accompanying drawings, forming a part thereof.

10 Figure 1 is a perspective view of my newly-designed standard, and Fig. 2 is a plan view of the same.

15 The general form of the standard is that of a truncated pyramid having a rectangular base considerably longer than it is wide. The sides, however, are slightly curved, especially at their upper ends. This slight curvature adds something to the generally symmetrical appearance of the standard, but does not 20 amount to departure from the general outline,

as above described. In the top a semi-cylindrical depression is formed. The ends A and sides B are smooth and without ornamentation, and their meeting edges are nicely finished.

25

The appearance of the standard thus described is graceful and symmetrical, and it is especially pleasing to the eye, because it creates the impression of well-proportioned strength and absolute stability. This last effect is intensified by a round hole through the standard.

30

What I claim as new, and desire to secure by Letters Patent, is—

35 The design for a pillow-block standard, substantially as shown and described.

HARRY W. HILL.
